UNITED STATES PATENT OFFICE.

FLOYD N. PERKINS, OF CLEVELAND, OHIO.

DESIGN FOR THE ORNAMENTATION OF SASH-LIFTS OR OTHER ARTICLES OF BUILDERS' HARDWARE.

SPECIFICATION forming part of Design No. 19,202, dated July 9, 1889.

Application filed May 13, 1889. Serial No. 310,646. Term of patent 3½ years.

To all whom it may concern:

Be it known that I, FLOYD N. PERKINS, a citizen of the United States, residing at Cleveland, in the county of Cuyahoga and State of Ohio, have invented and produced a new and original Design for Builders' Hardware, of which the following is a specification, reference being had to the accompanying drawings, forming part thereof.

10 In the drawings, Figure 1 is a front or face view of a hand-lift for window-sashes, adapted to be set in and about a recess in the base-rail of the lower sash of a window; and Fig. 2 is a transverse section of said plate.

15 The leading feature of my design consists in the matting figure-work which covers the face of the plate between its plain borders on the face proper and on the face of the socket portion.

20 A is the face proper of the hand-plate, which is rectangular in outline and provided with a plain border *b* along its edge and a similar border *c* around the oblong recess therein. Between these borders, on a slightly-depressed surface, is the matting ornamentation *e*. The lines of the matting run diagonally to the ends of the plate both right and left, so that they cross each other at right angles. Each line consists in two raised threads *f*, lying close together, with slight space between them, and a circular indentation *g* marks the angle where the sets of lines cross each other. In the center of the small squares

thus formed by the sets of lines is a slight quadrangular prism or projection *h*, which 35 has four inclined sides corresponding to the right-angled lines by which it is bordered. The effect is rich and pleasing to the eye.

The facing in the bottom of the recess, like the plate proper, has a plain border *k* and the 40 matting ornamentation *e* on a lower plane than the border, the same as on the surface of the plate proper.

The articles of builders' hardware to which the invention is applicable are such as sash-lifts, (shown in the drawings,) lock-fronts, door-hinges, escutcheons, and the like articles having exposed surfaces, upon which the ornamentation is placed with equal advantage, or according as said articles are more or 50 less exposed to view.

I claim—

The design for the ornamentation of sash-lifts and kindred articles of builders' hardware, as herein shown and described, the same 55 consisting of a matting figure on the surface of the article, formed by pairs of two parallel ribs crossing each other at right angles, a circular indentation in the angle of the ribs, and a slight projection in the block between the 60 pairs of ribs, having four inclined sides.

FLOYD N. PERKINS.
